CIRCUIT INTERRUPTER

Winthrop M. Leeds, Forest Hills, Pa., assignor to
Westinghouse Electric Corporation, East Pittsburgh, Pa., a corporation of Pennsylvania

Application August 15, 1944, Serial No. 549,575

14 Claims. (Cl. 200—150)

1

This invention relates to circuit interrupters in general and, more particularly, to arc extinguishing structures therefor.

A general object of my invention is to provide a circuit interrupter of improved construction which will interrupt more effectively the current passing therethrough than has been achieved heretofore.

Another object is to provide an improved circuit interrupter in which contact and piston means are operable to draw an arc and simultaneously force fluid adjacent the arc. Preferably the arc is rotated between a pair of ring-shaped contacts by magnetic means to not only minimize contact burning but also to render the flow of fluid more effective in bringing about arc extinction.

Another object is to provide an improved circuit interrupter in which improved operating means are utilized to effect an interruption of the circuit. More specifically, the operating means may establish two serially related arcs in sequence, the first established arc being subjected to deionizing action especially adaptable for high current interruption, whereas the second serially related arc is subjected to deionizing action which is especially adaptable for low current interruption. Preferably a single operating means is employed to draw the aforesaid two serially related arcs in sequence.

Another object is to provide an improved circuit interrupter of the type which establishes an arc and rotates the same between a pair of co-operable ring-shaped contacts. Preferably I employ piston means to effect a radial inward or a radial outward flow of fluid adjacent the established arc.

Another object is to provide an improved circuit interrupter in which a rotating arc is subjected to a longitudinal fluid blast. It has been found that if a radial flow of fluid is employed in extinguishing a rotating arc, the arc has a tendency to be bowed in the direction of the radial fluid blast and consequently to assume a configuration which is substantially parallel to the magnetic field. Such a bowing thus not only minimizes the effect of the transverse field necessary to continue rotation of the arc but also the bowed shape of the arc increases both the arc length and the arc power, especially during the peak of the alternating current wave.

It is an object of my invention to solve the aforementioned problem by subjecting the rotating arc to a fluid blast, which may be either gaseous or liquid longitudinally of said arc to elimi-

2

nate the tendency toward bowing. Preferably, I employ an annularly shaped orifice which more effectively directs the fluid blast toward the rotating arc to effect the extinction thereof.

5 Further objects and advantages will readily become apparent upon a reading of the following specification taken in conjunction with the drawings; in which:

Figure 1 shows a vertical sectional view through 10 a circuit interrupter embodying my invention and shown in the partly open circuit position;

Fig. 2 is a sectional view taken along the line II—II of Fig. 1;

Fig. 3 is a vertical sectional view through 15 a modified type of circuit interrupter embodying my invention and shown in the partly open circuit position;

Fig. 6 is a sectional view taken along the line VI—VI of Fig. 5.

25 Referring to the drawings and more particularly to Fig. 1 thereof, the reference numeral 1 designates an insulating cylindrical casing closed at its upper end by an insulating plate 2 and also closed at its lower end by a metallic cup-shaped member 3. An overpressure valve 4 is provided in the plate 2 and a gas venting check valve 5 is also provided in the plate 2. Movable through the plate 2 is an operating rod 6 composed of conducting material and having a vent 7 provided therethrough. The operating rod 6 carries a piston 8 rigidly secured thereto by a press fit having a flap valve 9 associated therewith. A strong compression spring 10 has its upper seat on a ring-shaped insulating plate 11 which is limited in travel by a shoulder in the cylinder wall 21. The lower end of the strong spring 10 is seated on a hollow operating member 12 composed of insulating material and having secured thereto at its lower end a movable 30 ring-shaped contact 13.

The contact 13 is cooperable with a relatively stationary ring-shaped contact 14 fixedly supported in place by an insulating plate member 15. Associated with the relatively stationary contact 14 is a series field coil 16. This coil when energized serves to provide a radial magnetic field between the contacts 13, 14. Associated with the movable contact 13 is another series field coil 17 wound so as to produce an opposing magneto-

35 motive force. This coil has its upper terminal 40 45 50 55

serially connected with a plurality of segmental fingers 18 collectively forming a contact which is carried by the operating member 12.

The operating member 12 is guided by an upstanding insulating cylindrical member 19, the latter being closed at its upper end by a ring-shaped insulating plate member 20 having integrally formed therewith an upstanding insulating cylindrical member 21 which serves to guide the piston 8. The operating rod 6 carries at its lower end a corrugated insulating follower 22. Also it will be observed that the upper portion 23 of the operating member 12 is corrugated. A plurality of rods 24 have their lower ends threadedly secured in the upper end of the operating member 12 and have their upper ends bent inwardly to serve as upper seats for a relatively weak compressor spring 25 which biases the operating member 12 to its upper position where it abuts against the plate 20.

In the closed circuit position of the interrupter, not shown, the electrical circuit therethrough comprises the operating rod 6, contact portion 26 thereof, segmental fingers 18, upper series field coil 17, movable contact 13, stationary contact 14, lower series field coil 16, to a conducting cup-shaped member 27 to the line terminal 28. In the closed circuit position of the interrupter the operating rod 6 is forced downwardly by suitable means not shown to a position which is farther downward than is shown in Fig. 1. In other words, the piston 8, through the cushioning spring 10, forces the operating member 12 downwardly so that the contacts 13, 14 make abutting engagement.

To open the circuit passing through the interrupter the operating rod 6 is moved upwardly to first permit the compression spring 25 to raise the operating member 12 being assisted in this action by the accelerating compression spring 29 which biases a conducting follower 30 upwardly. The separation between the contacts 13, 14 establishes an arc 31 therebetween which is rotated by the radial magnetic field set up by the series field coils 16, 17. The upward movement of the operating rod 6 carries the piston 8 therewith to cause a circulation of fluid, in this instance oil, upwardly in the region 32 through apertures 33 provided in the cylindrical member 21, downwardly through the annular region 34 and radially inwardly toward the arc 31 through apertures 35 provided in the cylindrical member 19. For relatively high amperage currents of the order of several thousand amperes or more, the rapid rotation of the arc in conjunction with the radial inward flow of the oil will serve to bring about extinction of the arc 31 and a consequent breaking of the electrical circuit passing through the interrupter. For lower amperage currents the magnetic field produced by the series field coils 16, 17 may be sufficiently weak so that interruption of the arc 31 may not take place.

In this event continuing upward movement of the operating rod 6 will serve to bring about a separation between the secondary contacts including the contact portion 26 of the rod 6 and the segmental contact 36 which is longer than the other segmental contacts 18. Thus an arc will be drawn between the secondary contacts 36 and 26 in the constricted portion of the operating member 12, the arc being forced against the corrugations provided by the follower 22 and the corrugations formed in the upper portion of the operating member 12 (note Fig. 2). The particular interrupting structure associated with the arc,

not shown, drawn between the secondary contacts 26, 36 is particularly adapted for low current interruption. Certain features of such an interrupting structure are disclosed and broadly claimed in United States Patent 2,253,009 which issued August 19, 1941 to Benjamin P. Baker and which is assigned to the assignee of the instant application.

During the downward stroke of the operating rod 6 the flap valve 9 will raise upwardly away from the piston 8 to provide unimpeded downward movement of the piston 8.

In the construction which I show herein, it will be noted that I have combined in a novel way three principles of alternating current circuit interruption in a single circuit interrupter. These three principles are: (1) fluid blast, which may be produced by piston action, compressed air, or an auxiliary series arc, (2) magnetic blow-out, produced by magnetic means to lengthen the arc, increase turbulence and de-ionization, and reduce contact burning, and (3) arc constriction, forcing the established arc through small holes, subjecting it to guillotine action, or constrictions as in the aforesaid patent.

Thus it is apparent that my invention covers a novel combination of all the three above-mentioned principles designed to produce rapid arc rupture over a wide current range, particularly at very high currents. It will be observed that the motion of the piston 8 circulates oil radially inwardly between the contacts 13, 14 driving products of arc combustion up around the operating rod 6 to the space below the piston 8 and also out the vent 7 provided in the operating rod 6. Preferably the velocity of the flow between the contacts 13, 14 should be high enough so that liquid replaces gas at a particular point in less than the time of one revolution of the arc. The turbulence of the arc 31 and the scavenging action of the liquid flow should be sufficient to interrupt the current at the first or second current zero. If this is not brought about, further upward movement of the rod 6 draws a second serially related arc between the secondary contacts 26, 36, which is constricted. This restriction will readily effect the extinction of low current arcs. Also the high velocity of the liquid blast caused by the circulation produced by the piston 8 will cooperate with the insulating corrugations to effect a ready extinction of the low current arc drawn between the secondary contacts 26, 36.

In the embodiment of my invention shown in Figs. 3 and 4 it will be noted that again the operating rod 6 has a vent 7 provided therethrough. But in this particular arrangement the vent 7 is closed by a valve 39 provided at the lower end of the operating rod 6 and biased to its closed position by a compression spring 40. As in the previous embodiment of my invention the piston 8 is operable during the closing stroke to force the cushioning spring 10 to cause downward movement of the operating member 12 to effect an engagement between the ring-shaped contacts 13, 14.

However, it will be noted that I have provided means forming an annular orifice through which the arc 31 is drawn and rotated by the series field coils 16, 17. Furthermore the fluid blast which is driven adjacent the arc 31 by the piston 8 strikes the arc 31 substantially longitudinally thereof to thus minimize bowing of the arc 31.

In United States Patent 2,333,598 which was issued November 2, 1943 to Albert P. Strom and

which is assigned to the assignee of the instant application, there is disclosed means for drawing an arc between ring-shaped contacts and rotating the arc about said ring-shaped contacts by a radial magnetic field. In this patent a fluid blast strikes the rotating arc radially inwardly or radially outwardly thereof. However, in the operation of such an interrupter under certain conditions, the most effective operation has not been obtained due to the bowing of the arc either inwardly or outwardly depending upon the direction of the radial fluid blast. Not only does the bowing of the arc force it to assume a configuration which is parallel to the magnetic field but also the extreme length of such a bowed arc causes the interrupter to dissipate considerable energy especially during the peak of the alternating current wave because of the considerable arc voltage. In the construction which I show in Fig. 3 it will be observed that the fluid flow is substantially longitudinally of the rotating arc 31 as it rotates about the contacts 13, 14 within the annularly shaped orifice 41. This results from the merger of the fluid flow upwardly through the inner and outer annular passages 46. Thus there is no bowing of the arc and by the provision of the annularly shaped orifice 41 the fluid blast is very effectively directed toward the arc 31.

It will also be observed that valves 42 are provided in the annular region 34 and that ball valves 43 are provided in the plate member 2. By such a construction it will be apparent that downward movement of the operating rod 6 will serve to draw liquid, in this instance oil, through the ball valves 43 from the region 44 to the region 45, the valves 42 remaining closed during this time. Thus fresh oil of high dielectric strength is brought into the region 45.

During the opening operation upon upward movement of the operating rod 6 the upward movement of the piston 8 will effect a closure of the ball valves 43 and an opening of the valves 42. The result is a unidirectional flow of oil from the region 45 through the valves 42 downwardly through the annular region 34 and upwardly through the inner and outer annular passage 46, and upwardly through the annular orifice 41 adjacent the arc 31. This oil flow may continue upwardly through passages 47 to the region 48 below the upwardly moving piston 8. Thus there is a circulation of oil during the opening operation. During a subsequent closing operation the downward movement of the piston 8 will cause closure of the valves 42 and the passage of oil through the valve 39 through the vent 7 and out the apertures 49.

Circuit breakers using liquid flow, preferably oil, set in motion by a powerful piston for arc rupturing purposes are sometimes referred to as "impulse" type breakers. Commercial designs of these impulse breakers utilize oil flow in the order of 100 feet per second requiring very high mechanical driving force behind the oil piston. This embodiment of my invention covers, it will be observed, a more moderate oil flow type breaker with a magnetic field aiding by rotating the arc while it is being subjected to a longitudinal oil flow. Experimental results have shown that a rotating arc can be interrupted with considerably reduced oil velocity as compared to an arc held stationary in a circular orifice. Consequently, by employing a rotating arc construction in combination with a longitudinal oil flow, the interrupter renders increased interrupting performance with comparatively low oil velocity.

In the closed circuit position of the interrupter, not shown, in Fig. 3 the electrical circuit therethrough comprises the operating rod 6, segmental fingers 18, upper series field coil 17, movable annular contact 13, stationary annular contact 14, lower series field coil 16, connector 50, conducting cup-shaped member 51 to the line terminal 52.

In the construction shown in Figs. 5 and 6 it will be observed that I have provided an insulating 10 casing 55 closed at its upper end by a conducting plate 56 provided with ball valves 57 and through which operates a conducting operating rod 58. The rod 58 carries a piston 59 at its lower end having a flap valve 60 associated therewith. The 15 piston 59 operates within a conducting piston cylinder 61 having apertures 62 provided at its upper end. The lower portion 63 of the cylinder 61 forms a hollow stationary contact which is cooperable with a movable contact 64 spring-biased to its upper position by a compression 20 spring 65 having a lower seat on a conducting dome-shaped member 66.

Disconnect means generally designated by the reference numeral 67 are associated with the 25 operating rod 58 in a manner hereinafter described. The disconnect means 67 comprise a stationary disconnect contact 68 cooperable with a movable disconnect blade 69 pivotally mounted at 70 to a fixed pivot. The disconnect blade 69 30 may be latched in its open position by latching means generally designated by the reference numeral 71. In this instance the latching means 71 comprises a bell-crank member 72 pivotally mounted at 73 to a fixed pivot. The bell-crank 35 72 is pivotally connected to a link 74 the other end of which is pivotally connected at 75 to a second bell-crank 76 pivotally mounted at 77 to a fixed pivot. The bell-crank 76 is biased in a counterclockwise direction about the pivot 77 by 40 a compression spring 78 having its other seat against an insulating cylindrical member 79 which serves to contain a suitable arc extinguishing liquid which may be oil. The operating rod 58 carries a flange 80 rigidly secured thereto and 45 a washer 81 slidably movable thereon, being biased upwardly by a compression spring 82 having a lower seat against a flange 83 rigidly secured to the operating rod 58.

In the closed circuit position of the interrupter, 50 not shown, the electrical circuit therethrough comprises stationary disconnect contact 68, disconnect blade 69, washer 81, conducting operating rod 58, conducting plate 56, conducting piston cylinder 61, stationary contact 63, movable contact 64, flexible connectors 84, conducting plate 85, to the line terminal 86.

During the opening operation suitable means, 55 not shown, causes downward movement of the operating rod 58. The downward movement of the rod 58 causes downward movement of the piston 59 which forces oil downwardly in the direction shown by the arrows in Fig. 5 to cause opening movement of the movable contact 64 against the biasing action exerted by the compression spring 65. This draws an arc, the original terminal positions of which are at the points 87, 88. However, the radially outward flow of oil carries the arc outwardly to cause it to extend between the ring-shaped contacts 89 and 90 around which it is 65 rotated by the field coils 91, 92, which are cut into series circuit following transfer of the arc 93 to the contacts 89, 90. Thus in the closed position the field coils 91, 92 are shorted out, and they are 70 only inserted in the series circuit following transfer of the arc to the contacts 89, 90.

The radial magnetic field set up by the field coils 91, 92 rotates the arc 93 about the ring-shaped contacts 89, 90 while the piston 59 subjects said rotating arc 93 to a radial outward fluid blast. A ring-shaped splitter 94 formed of insulating material prevents the arc 93 from bowing outwardly.

During the last portion of downward travel of operating rod 58, the flange 80 picks up the movable disconnect blade 69 and causes it to separate from the stationary disconnect contact 68 thereby introducing an isolating gap into the electrical circuit following interruption of the arc 93. This is necessary inasmuch as when the piston 59 ceases its downward movement the compression spring 65 will cause a reengagement between the contacts 63, 64. During the subsequent closing operation the operating rod 58 is moved upwardly by suitable means, not shown. During the initial portion of the closing stroke the disconnect blade 69 remains latched open. During this portion of the closing stroke the washer 81 remains in abutting engagement with the movable disconnect blade 69 compressing the spring 82 until the flange 80 trips the bell-crank 72 to effect a clockwise movement of the bell-crank 76 about the pivot 77. When this occurs the movable disconnect blade 69 will be released from its latched position and the compression spring 82 will force the disconnect blade 69 into engagement with the stationary disconnect contact 68 by a snap action.

In this embodiment of my invention it will be apparent that again I have provided novel piston means for not only effecting the establishment of an arc but also providing fluid motion to effect the extinction of said arc. The structure is simple and positive in operation and the disconnect means 67 insures that an isolating gap will be provided prior to reclosure of the contacts 63, 64.

My arrangement has the advantage over the use of the ordinary magnetic blowout which is weak at low currents, and in which at high currents, the arc lengthening takes place so rapidly as to produce excessively high pressures in the breaker. I have made unnecessary the use of a piston and driving mechanism large enough to interrupt the maximum rupturing capacity current, and have avoided the use of all this effort even on low power switching operations.

The construction disclosed in Fig. 5 describes a new type of high speed interrupter which requires only a moderate size operating mechanism and utilizes a radial magnetic field for rotating the arc without lengthening it so as to interrupt high currents with the liberation of only a reasonably small amount of arc energy. It will be observed that the radial magnetic field rotates the arc at high speed while the oil flow scavenges the arc products, driving them out of passages on either side of the arc splitter. Ten to twenty feet per second linear oil velocity at the splitters should be adequate, compared to seventy-five to one-hundred feet per second required by a straight oil blast device. The high relative velocity between arc and oil required for high current interruption is provided by the rapid arc motion on the annular arc horns.

For low current interruption where the magnetic action is weak, the arc is extinguished by the cross-blast oil flow alone produced by the piston 59.

From the above construction it will be apparent that I have provided novel disconnect means in

which the disconnect switch blade is latched open and does not move during the first part of the closing stroke, but the spring 82 under the switch blade is merely compressed. The flap valve 60 associated with the piston 59 permits the piston to move upward freely during the closing stroke. Since pressure due to the gas generation is communicated to both sides of the piston 59 during the opening operation, there is no appreciable tendency to slow down the operation.

From the foregoing description of several embodiments of my invention it will be apparent that I have provided a circuit interrupter of improved construction in which the arc established during the opening operation is rotated while simultaneously being subjected to a fluid blast which may be radially inwardly, radially outwardly or longitudinally of the established arc. By the use of a single operating means to effect the extinction of the arc and the fluid flow, it will be noted that the construction is exceedingly simple in operation and effective in performance.

Although I have shown and described specific structures, it is to be clearly understood that the same were merely for the purpose of illustration and that changes and modifications may readily be made therein by those skilled in the art without departing from the spirit and scope of the appended claims.

I claim as my invention:

1. In a circuit interrupter of the liquid break type, a substantially enclosed casing, an operating rod movable through a wall of the casing, a liquid moving piston secured to and movable with the operating rod within the casing, a cylinder within which the piston moves to drive liquid, a relatively stationary ring-shaped contact, an operating member carrying a movable ring-shaped contact and adapted for limited movement axially of the casing, biasing means surrounding the cylinder biasing the operating member and movable ring-shaped contact to the open position, a resilient means interposed between the piston and the operating member so that closing movement of the operating rod will effect through the resilient means closing motion of the operating member and movable ring-shaped contact against the biasing action exerted by the biasing means, and liquid passage means communicating at one end with the piston movable within the cylinder and at the other end with the two ring-shaped contacts.

2. In a circuit interrupter of the liquid break type, a substantially enclosed casing, an operating rod movable through a wall of the casing, a liquid moving piston secured to and movable with the operating rod within the casing, a cylinder within which the piston moves to drive liquid, a relatively stationary ring-shaped contact, an operating member carrying a movable ring-shaped contact and adapted for limited movement axially of the casing, biasing means surrounding the cylinder biasing the operating member and movable ring-shaped contact to the open position, a resilient means interposed between the piston and the operating member so that closing movement of the operating rod will effect through the resilient means closing motion of the operating member and movable ring-shaped contact against the biasing action exerted by the biasing means, and liquid passage means communicating at one end with the piston movable within the cylinder and at the other end with the two ring-shaped contacts, means providing a radial

magnetic field to cause rotation of the arc around the ring-shaped contacts, and a vent through the operating rod permitting exhaust of liquid out of the casing.

3. In a circuit interrupter of the liquid break type, a substantially enclosed casing, an operating rod movable through a wall of the casing, a liquid moving piston secured to and movable with the operating rod within the casing, a cylinder within which the piston moves to drive liquid, a relatively stationary ring-shaped contact, an operating member carrying a movable ring-shaped contact and adapted for limited movement axially of the casing, biasing means surrounding the cylinder biasing the operating member and movable ring-shaped contact to the open position, a resilient means interposed between the piston and the operating member so that closing movement of the operating rod will effect through the resilient means closing motion of the operating member and movable ring-shaped contact against the biasing action exerted by the biasing means, and liquid passage means communicating at one end with the piston movable within the cylinder and at the other end with the two ring-shaped contacts, means for causing rotation of the arc around the ring-shaped contacts, a movable secondary contact carried by the operating rod, and a relatively stationary secondary contact cooperable therewith and carried by the operating member.

4. In a circuit interrupter, a relatively stationary ring-shaped contact, a movable ring-shaped contact separable from the stationary ring-shaped contact to establish an arc, means for causing only a radial inward flow of fluid between the separated contacts, venting means communicating with the interior of the movable ring-shaped contact, and a member of insulating material positioned at least part of the time of the interruption process within the movable ring-shaped contact closely adjacent thereto to confine and restrict the terminal of the arc playing on the movable ring-shaped contact.

5. In a circuit interrupter, a pair of ring-shaped contacts, means for establishing an arc between the ring-shaped contacts, means for causing a rotation of the arc around the ring-shaped contacts, venting means communicating with the interior of one of the ring-shaped contacts, means for causing only a radially inwardly directed flow of fluid between the contacts and out through the venting means, and a member of insulating material positioned during a portion of the time of the interruption process within said one of the ring-shaped contacts closely adjacent thereto to confine one terminal of the rotating arc.

6. In a circuit interrupter, a pair of ring-shaped contacts, means for establishing an arc between the ring-shaped contacts, means for causing a rotation of the arc around the ring-shaped contacts, venting means communicating with the interior of one of the ring-shaped contacts, means for causing a radially inwardly directed flow of fluid between the contacts, and a member at least partially of insulating material positioned during a portion of the time of the interruption process within said one of the ring-shaped contacts, and the member having a plurality of corrugations thereon.

7. In a circuit interrupter, a relatively stationary ring-shaped contact, an operating member carrying a movable ring-shaped contact and adapted for limited axial movement, means for providing a radial inwardly directed fluid flow

between the ring-shaped contacts, venting means communicating with the interior of the movable ring-shaped contact, means for rotating the arc around the ring-shaped contacts, an operating rod carrying an insulating follower member extending within the movable ring-shaped contact at least in the closed position of the interrupter, means biasing the operating member to the open position, and the operating rod causing closing movement of the operating member against the biasing action exerted by the biasing means.

8. In a circuit interrupter, a relatively stationary ring-shaped contact, an operating member carrying a movable ring-shaped contact and adapted for limited axial movement, means for providing a radial inwardly directed fluid flow between the ring-shaped contacts, venting means communicating with the interior of the movable ring-shaped contact, means for rotating the arc around the ring-shaped contacts, an operating rod carrying an insulating follower member extending within the movable ring-shaped contact at least in the closed position of the interrupter, means biasing the operating member to the open position, and resilient means stronger than the biasing means interposed between the operating rod and the operating member.

9. In a circuit interrupter, a relatively stationary ring-shaped contact, an operating member carrying a movable ring-shaped contact and adapted for limited axial movement, means for providing a radial inwardly directed fluid flow between the ring-shaped contacts, venting means communicating with the interior of the movable ring-shaped contact, means for rotating the arc around the ring-shaped contacts, an operating rod carrying an insulating follower member extending within the movable ring-shaped contact at least in the closed position of the interrupter, means biasing the operating member to the open position, the operating rod causing closing movement of the operating member against the biasing action exerted by the biasing means, and a pair of separable secondary contacts carried respectively by the operating rod and operating member.

10. In a circuit interrupter, a relatively stationary ring-shaped contact, an operating member carrying a movable ring-shaped contact and adapted for limited axial movement, means for providing a radial inwardly directed fluid flow between the ring-shaped contacts, venting means communicating with the interior of the movable ring-shaped contact, means for rotating the arc around the ring-shaped contacts, an operating rod carrying an insulating follower member extending within the movable ring-shaped contact at least in the closed position of the interrupter, means biasing the operating member to the open position, resilient means stronger than the biasing means interposed between the operating rod and the operating member, and a pair of separable secondary contacts carried respectively by the operating rod and operating member.

11. In a circuit interrupter of the liquid break type, a relatively stationary ring-shaped contact, a hollow insulating operating member carrying a movable ring-shaped contact adjacent one end thereof and being interiorly grooved adjacent the other end thereof, means allowing only limited axial movement of the hollow operating member, means for rotating the arc around the ring-shaped contacts, means for causing a radially inwardly directed liquid flow between the separated ring-shaped contacts, and an operat-

ing rod carrying a follower member extending through the hollow insulating operating member for causing the operating movement thereof, a secondary contact carried by the hollow operating member, and a cooperable secondary contact carried by the operating rod.

12. In a circuit interrupter of the liquid break type, a relatively stationary ring-shaped contact, a hollow insulating operating member carrying a movable ring-shaped contact adjacent one end thereof and being interiorly grooved adjacent the other end thereof, means allowing only limited axial movement of the hollow operating member, means for rotating the arc around the ring-shaped contacts, means for causing a radially inwardly directed liquid flow between the separated ring-shaped contacts, and an operating rod carrying a follower member extending through the hollow insulating operating member for causing the operating movement thereof, a secondary contact carried by the hollow operating member, a cooperable secondary contact carried by the operating rod, and the follower member also being grooved to constrict the arc drawn by the secondary contacts.

13. In a circuit interrupter of the liquid break type, a relatively stationary ring-shaped contact, a hollow insulating operating member carrying a movable ring-shaped contact adjacent one end thereof, means allowing only limited axial movement of the hollow operating member, means for rotating the arc around the ring-shaped contacts, means for causing a radially inwardly directed liquid flow between the separated ring-shaped contacts, and an operating rod carrying a follower member extending through the hollow insulating operating member for causing the operating movement thereof, a secondary contact carried by the hollow operating member, and a cooperable secondary contact carried by the operating rod.

14. In a circuit interrupter, a relatively stationary ring-shaped contact, means defining an annular orifice and shielding the aforesaid ring-shaped contact, another ring-shaped contact, means for establishing an arc between the two ring-shaped contacts, means for rotating the arc around the ring-shaped contacts, passage means within the annular orifice on both the inner and outer sides of the stationary ring-shaped contact to direct fluid in two annular converging jets to flow out of the annular orifice longitudinally of the rotating arc and toward the other ring-shaped contact, the region outside of the annular orifice and between the two contacts being at relatively low pressure.
